CLAIM

I claim the ornamental design for a hearing aid, as shown and described.

DESCRIPTION

FIG. 1 is a top perspective view of a hearing aid of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a front view thereof shown in an environmental use.

The broken line showing of hearing aid is included for the purpose of illustrating environment and forms no part of the claimed design.
